UNITED STATES PATENT OFFICE.

JOSEPH FRANK HARRINGTON, OF KILLINGLY, CONNECTICUT.

LUG-STRAP ATTACHMENT.

No. 813,417.

Specification of Letters Patent.

Patented Feb. 27, 1906.

Application filed July 6, 1904. Serial No. 215,477.

To all whom it may concern:

Be it known that I, JOSEPH FRANK HARRINGTON, a citizen of the United States, residing at Killingly, in the county of Windham and State of Connecticut, have invented 5 a new and useful Lug-Strap Attachment, of which the following is a specification.

This invention relates to the mechanism employed in a loom for connecting the sweep- 10 stick with the picker-staff and is applicable to all kinds of wool, cotton, linen, silk, jute, ramie, and carpet picker-staff looms.

The object of this invention is to provide a mechanism for connecting the sweep-stick 15 with the picker-staff which can be easily and quickly adjusted and which will lengthen the life and increase the efficiency of the picker-staff and lug.

The embodiment of the invention that is 20 illustrated by the accompanying drawings has a link which adjustably connects an arm that is fastened to the lug-strap with an arm that is adjustably attached to the lower part of the lathe or rocker, whereby the level of 25 the point of engagement of the lug-strap with the picker-staff may be changed without stopping the loom and the engagement so effected that the speed of the picker increases as the picker-staff is swept across by the sweep- 30 stick for throwing the shuttle.

Figure 1 of the illustrations shows an outline of an adjustable lug-strap attachment which embodies the invention with so much of a loom as is necessary to comprehend the 35 invention. Fig. 2 shows a view of the same with the picker-staff thrown over. Fig. 3 shows a view of the lug-arm. Fig. 4 shows a view of the lock and rocker-arm, and Fig. 5 shows a section of the lock which fastens the 40 link to the rocker-arm.

In the mechanism illustrated the picker-staff 1 is hung in a common manner at the base of the lathe or the part of the loom commonly known as the "rocker," so that it may 45 be swept over for impelling a shuttle from the shuttle-box 2 along the shuttle-race 3 in the usual way by a sweep-stick 4, which is connected with any suitable power mechanism. The staff shown is drawn back by a 50 strap 5 and spring 6.

The lug-strap 7, which preferably consists of several plies of leather, canvas, rubber, or similar materials which are commonly used for the purpose, is fastened to the end of the 55 sweep-stick and loops about the picker-staff, as usual.

Previously the means most commonly employed for holding the lug-strap upon the picker-staff has been a flexible loop known as a "power-strap." This invention eliminates 60 the power-strap and substitutes a connection which is more durable and satisfactory and easier to adjust.

In the form of connection which is illustrated in the accompanying drawings there is 65 an arm 8 fastened to one side of the lug-strap. It is preferred to fasten this arm by means of the bolt 9, that joins the lug-strap to the end of the sweep-stick, and by prongs 10, which are made to extend from the arm into the 70 material of the lug-strap, so that the lug-strap and arm move together. The outer end of the lug-arm 8 is pivoted to the upper end of a link 11. The lower end of the link shown has teeth on one edge and extends 75 through a mortise in the lock-plate 12, which is pivoted to the outer end of an arm 13, that is secured to the rocker, preferably by the same bolt 14 that pivots the picker-staff. The bolt 14 extends through a slot in the 80 rocker-arm and into the rocker, so that the arm may be adjusted longitudinally. The lock-plate has a stud 15, that extends into the mortise in position to engage with the teeth on the link, and has a spring 16, which thrusts 85 between a screw 17 and a shoe 18, that bears against the edge of the link for causing an engagement of the teeth and the stud.

The length of the link between the lug-arm 8 and the rocker-arm 13 is adjusted by pulling the lower end of the link back against the spring in the lock-plate and releasing the teeth from the stud and then raising or lowering the link. When the link is released, the spring causes an engagement of the teeth 95 and stud, which locks them together. The height of the upper end of the link determines the point of engagement of the lug-strap with the picker-staff, and the adjustment of the rocker-arm fixes the distance of the axis 100 of the lower end of the link from the axis of the picker-staff.

If the picker or the sweep-stick operating parts wear or if for any other reason it is desired to alter the speed, power, or throw of 105 the picker-staff, the link may be adjusted by grasping its lower end and disengaging the teeth and stud and lowering or raising it until the stud will engage the necessary teeth and hold the link, with the lug-arm and lathe- 110 arm, the proper distance apart.

As the picker-staff in the form of the inven-

tion illustrated in the drawings is swung over the lug-arm swings downwardly and draws the lug downwardly on the picker-staff, and of course as the lug is lowered the speed of the picker at the upper end of the picker-staff increases—that is, the speed of the upper end of the picker-staff increases rather than diminishes as it sweeps forward, which is very desirable in order that the shuttle may be properly thrown with a minimum amount of wear.

The speed of the upper end of the picker-staff is regulated by changing the distance between the axis of the lower end of the link and the axis of the picker-staff, and if the axes of the picker-staff and lower end of the link are coincident the speed of the upper end of the picker-staff will be uniform during its entire sweep.

20. The employment of this construction allows the point of application of power on the picker-staff to be varied as desired without stopping the loom and without making holes in or injuring the picker-staff, which lengthens the life of the staff, reduces wear on the lug, and prevents the breaking of picker-staffs and "loom-smashes," and thus increases the capacity of the loom. It also permits the regulation of the initial impulse given the shuttle and the regulation and control of the speed of the picker-staff during the entire throw of the shuttle, as different kinds of filling and varying circumstances may require.

35. The invention claimed is—

1. In a loom, the combination with a lug-strap of flexible material and an ordinary rocker, of an arm attached to the inner end of the flexible lug-strap and extending outwardly beyond the picker-stick, and a link pivotally connected with the outer end of the arm and extending outside the picker-stick to and pivotally connected with the rocker; substantially as specified.

45. 2. In a loom, in combination, a lug-strap of flexible material, an ordinary rocker, an arm attached to the inner end of the flexible lug-strap and extending outwardly beyond the picker-stick, and an adjustable link pivotally connected with the outer end of the arm and extending outside of the picker-stick to and pivotally connected with the rocker, substantially as specified.

55. 3. A lug-strap support having an arm adapted to be attached to the inner end of and to extend outwardly beyond the outer end of the ordinary flexible lug-strap, an arm adapted to be connected with and to extend outwardly beyond the ordinary rocker, and a link connecting the lug-strap arm with the rocker-arm outside the picker-stick, substantially as specified.

65. 4. A lug-strap support having an arm adapted to be attached to the inner end of and to extend outwardly beyond the outer

end of the ordinary flexible lug-strap, an arm adapted to be adjustably connected with and to extend outwardly beyond the ordinary rocker, and a link connecting the lug-strap arm with the rocker-arm outside of the picker- 70 stick, substantially as specified.

5. A lug-strap support having an arm adapted to be attached to the inner end of and to extend outwardly beyond the outer end of the ordinary flexible lug-strap, an arm adapted to be connected with and to extend outwardly beyond the ordinary rocker, and an adjustable link connecting the lug-strap arm with the rocker-arm outside of the picker- 75 stick, substantially as specified. 80

6. A lug-strap support having an arm adapted to be attached to the inner end of and to extend outwardly beyond the outer end of the ordinary flexible lug-strap, an arm adapted to be connected with and to extend outwardly beyond the ordinary rocker, and a link pivoted to one arm and adjustably connected with the other arm outside of the picker-stick, substantially as specified. 85

7. A lug-strap support having an arm with a bolt-hole and prongs whereby it may be connected with the inner end of and may extend outwardly beyond the outer end of the ordinary flexible lug-strap, an arm with a bolt-hole whereby it may be connected with 90 and extend outwardly beyond the ordinary rocker, and a link pivoted to one arm and adjustably connected with the other arm outside of the picker-stick, substantially as specified. 95

8. A lug-strap support having an arm adapted to be attached to the inner end of and to extend outwardly beyond the outer end of the ordinary flexible lug-strap, an arm adapted to be adjustably connected with and to extend outwardly beyond the ordinary rocker, and a link pivoted to one arm and adjustably connected with the other arm outside the picker-stick, substantially as specified. 105 100

9. A lug-strap support having an arm adapted to be attached to the ordinary flexible lug-strap, an arm adapted to be connected with the ordinary rocker, a lock-plate connected with one arm, a link connected with the other arm and extending through the lock-plate, the lock-plate and link having an engaging stud and teeth, and a spring for normally holding the stud engaged with the teeth, substantially as specified. 115 110

10. A lug-strap support having an arm adapted to be attached to the ordinary flexible lug-strap, an arm adapted to be connected with the pivot of the picker-staff, a lock-plate connected with the latter arm and provided with a stud and a spring, and a link pivoted to the lug-arm and extending through the lock-plate and provided with teeth that are adapted to engage the stud on the lock-plate, substantially as specified. 125 120 130

11. A lug-strap support having an arm adapted to be attached to the ordinary flexible lug-strap, an arm adapted to be fastened to the ordinary rocker, a lock-plate connected with one arm, a link connected with the other arm and adapted to be connected with the lock-plate, and a spring for normally holding the lock-plate and link together, substantially as specified.
12. The combination of a picker-staff, a sweep-stick, a flexible lug-strap attached to the sweep-stick and embracing the picker-
- staff, a rocker, an arm connected with and extending outwardly from the flexible lug-strap beyond the picker-stick, and a link pivotally connected with the outer end of the arm outside the picker-stick and adjustably connected with the rocker outside of the picker-stick, substantially as specified. 15
